APPARATUS FOR TWISTING AND REELING MATERIAL

Fred V. Johnson, deceased, late of Baltimore, Md., by Lila T. Johnson, executrix, Baltimore, Md., assignor to Western Electric Company, Incorporated, New York, N. Y., a corporation of New York

Application December 13, 1938, Serial No. 245,541

12 Claims. (Cl. 57—71)

This invention relates to apparatus for twisting and reeling material and more particularly to apparatus for reeling material under a predetermined tension and simultaneously imparting a spiral twist to the material being reeled.

It is an object of the present invention to provide a simple and efficient apparatus for twisting and reeling material.

In accordance with one embodiment of the invention, there is provided a reel cradle for rotatably supporting a reel and designed to be rotated about an axis at right angles to the axis of the rotation of the reel while the reel, during its rotation in the cradle, may be shifted transversely of the axis of rotation of the cradle to distribute the material being reeled and twisted onto the reel. The drive for the reel cradle is positive, whereas the drive for the reel mounted on the cradle may be regulated by a walking gear, which travels about an idler when sufficient braking force is applied to the idler, and in so traveling, will drive the reel. When the tension on the reel reaches a predetermined value, the brake will tend to slip, thereby maintaining constant tension on the material being wound.

A better understanding of the invention may be had by reference to the following detail description when considered in conjunction with the accompanying drawings, wherein

30 Fig. 1 is a plan view of a twisting takeup mechanism made in accordance with the present invention and adapted for use in conjunction with mechanism for assembling four wires spaced one from another by a plurality of spacers positioned 35 between them at regular intervals throughout the length of wires;

Fig. 2 is a side elevational view of the twisting takeup mechanism shown in Fig. 1, part of the view being cut away to conserve space;

40 Fig. 3 is an enlarged fragmentary side elevational view, partly in section, of the twisting takeup mechanism, as viewed along the line 3—3 of Fig. 1 in the direction of the arrows;

Fig. 4 is a fragmentary sectional view taken 45 along the line 4—4 of Fig. 3 in the direction of the arrows;

Fig. 5 is a fragmentary vertical sectional view taken on the line 5—5 of Fig. 3 in the direction of the arrows on a somewhat reduced scale;

50 Fig. 6 is an enlarged fragmentary sectional view taken on the line 6—6 of Fig. 4 in the direction of the arrows;

Fig. 7 is a sectional view taken on the line 7—7 of Fig. 6 in the direction of the arrows;

55 Fig. 8 is a fragmentary sectional view taken on

the line 8—8 of Fig. 4 in the direction of the arrows;

Fig. 9 is an enlarged view of a cable of the type which is handled by the apparatus shown in the other views; and

Fig. 10 is an enlarged sectional view taken through the cable shown in Fig. 9, the section being enlarged and the dimensions of some of the parts being exaggerated to show them more clearly.

Referring to the drawings, wherein like parts have been assigned like reference numerals, Figs. 1 and 2 show generally the takeup end of a cable manufacturing machine in which a cable 20, such as is shown in Figs. 9 and 10, may be made. It 15 will be noted that the cable 20 comprises four wires 21, 22, 23 and 24 wedged into slots 25, 26, 27 and 28, respectively, in spacers 29 and sheathed with overlapping layers of conducting and insulating material 30, 31, 32, 33 and 34 applied there- 20 to in tape form and wrapped spirally thereon. The wires and spacers are assembled by suitable mechanism (not shown) positioned to the left of the apparatus shown in Fig. 1 and are directed to ironing rollers 40—40, which engage in the 25 slots in the spacers and serve to hold the assembled wires and spacers from rotating about the axis of the assembled elements at this point.

The twist is imparted to the cable 20 in the area between the rollers 40—40 and a reel 41, 30 on which the cable is being wound, by rotating the reel at right angles to its axis during its rotation about its axis. In this area, the tapes are wrapped upon the wires and spacers by taping heads 42, 43 and 44, through which the assembled spacers and wires are directed to the reel 41. An understanding of the details of construction of the taping heads is not necessary to an 35 understanding of the present invention, and therefore it will suffice to say that the tapes are applied to the cable while the twist is being imparted to it, the cable being drawn through the various taping heads by the reel 41.

The apparatus for twisting and reeling the cable 20 is driven by a motor 50 (Fig. 1), mounted upon a suitable framework 51, and driving a chain 52, which drives a sprocket 53 mounted upon an auxiliary drive shaft 54. The auxiliary drive shaft 54 carries a gear 55, which meshes with a gear 56 mounted upon a main drive shaft 50 57. The auxiliary drive shaft 54, as is shown in Fig. 1, drives two of the taping heads, whereas the takeup and twisting mechanism and the other taping head are driven from the main drive shaft 57. The reel 41 is mounted in a cradle 75 in a 55

manner to be explained hereinafter. The cradle 75 has a tubular projection 76 extending to the left therefrom (Fig. 3) on which the entire cradle and its associated parts are mounted. The tubular projection 76 is mounted to rotate within a bearing 77 mounted upon a standard 78. The left end (Fig. 3) of the projection 76 has a guide member 79 threaded therein for guiding the completed cable 20 to the takeup reel 41 on the cradle 75. Fixed to the cradle 75 is a sprocket 82 adapted to be driven by a chain 83. The chain 83, in the embodiment of the invention shown, is driven by a sprocket mounted on the end of a shaft 84 (Fig. 1) suitably journaled in the supporting framework 51. The shaft 84 carries, at its left end (Fig. 1), a gear 85, which meshes with a gear 86 mounted on a shaft 87, which is geared to the main drive shaft 57 by means of gears 88 and 89. The driving connection just described will rotate the entire cradle 75 in one direction to impart a twist to the cable 20. If it is desired to twist the cable in the opposite direction, the shaft 84 may be shifted to the position in which the shaft 87 is now shown and the shaft 25 87 eliminated, whereby the cradle 75 will be rotated in the opposite direction. Any suitable chain-tightening device may be used for tightening the chain 83 on its sprocket 82 to compensate for the shifting of the shaft 84 from one position 30 to another, as just described.

Rotatable on the outer surface of the bearing 77 (Figs. 3 and 5) is a brake drum 90, which has cooperating therewith a pair of brake shoes 91 and 92 mounted intermediate the ends of pivoted brake arms 93 and 94, respectively. The brake arms are pivoted at 95 and 96 adjacent their lower ends and are connected at their upper ends to a pair of sleeves 97 and 98, respectively. The sleeve 98 is held on the end of a 40 brake rod 99 by means of a pair of nuts 100 and 101, and the sleeve 97 is slidable on the brake rod 99, which is threaded at its left end (Figs. 4 and 5) to receive a threaded hand wheel 102, between which and the sleeve 97 there is interposed a coiled spring 103 encircling the brake rod 99. By tightening or loosening the hand wheel 102, any desired tension may be applied to the brake drum 90 by means of the just-described mechanism.

50 The brake drum 90 carries a ring gear 104 which meshes with a gear 105 mounted upon a shaft 106 (Fig. 6) journaled in a bearing block 107, which is fixed in an aperture 108 in the cradle 75. The bearing block 107 carries a normally unused idler gear 109 having relatively wide teeth 110, which, as shown in Fig. 6, are out of mesh with the gear 105, which, as shown in Fig. 3, meshes with the ring gear 104. The idler 55 109 is mounted upon a stud shaft 111, fixed in the bearing block 107, and serves no purpose when it is mounted as shown in Figs. 3 and 6. However, if the direction of twist imparted to the cable is reversed by changing the position of shaft 84, it is necessary to change the direction of drive of the takeup reel 41 to compensate for the change in direction of twist imparted to the cable. This may be accomplished by reversing the gears 105 and 109, that is, turning them end for end on their respective shafts. This will cause the gear 105 to fall into a plane 60 where it is out of mesh with the gear 104, but in mesh with the teeth of the gear 109 and the teeth 110 of the gear 109 will be in mesh with the ring gear 104. From the foregoing, it is believed to be apparent that regardless of the

direction of twist imparted to the cable, the shaft 106 will be rotated in the same direction if the proper gear changes are made.

Carried by the shaft 106 (Fig. 6) on the end opposite the end on which the gear 105 is mounted, is a beveled gear 120, which meshes with a pair of beveled gears 121 and 122 rotatable in a transmission housing 123. The gear 121 is keyed to a shaft 124 and has formed on its left face (Fig. 6) a toothed clutch 125, which, as shown, is in engagement with a clutch member 126 slidably keyed to the end of a shaft 127, which is journaled in and freely rotatable in the gear 122. The clutch member 126 has formed on its left end clutch teeth 128 adapted to cooperate with the teeth of a clutch 129 formed on the right-hand face (Fig. 6) of the gear 122 when the clutch member 126 is shifted to the left (Fig. 6). The shaft 124 drives the takeup reel 41 through a roller chain 130, which meshes with a sprocket 131 secured to a collar 132 (Figs. 4 and 8). The shaft 124 is square in the area thereof surrounded by the collar 132 and is engaged by four rollers 133—133, which are rotatable in the collar 132 so that the collar will slide freely along the shaft 124, as the cable 20 is distributed on the reel 41. The sprocket 131 and its supporting collar 132 are mounted within a casing 134, fixed to a reel supporting frame composed of angle members 135, 136, 137 and 138. The angle members 135 and 136, as shown in Fig. 3, are irregular in shape and extend outwardly to the right from the angle members 137 and 138 to provide a pair of vertically disposed surfaces 139 and 140 (Figs. 1, 2, 3 and 4) on which reel journal blocks 144 and 145, respectively, are mounted. Rotatably mounted in the reel journal blocks 144 and 145 (Fig. 4) are a pair of bearings 146 and 147, respectively, having a reel supporting screw 148 mounted therein. The screw 148 is provided with an enlarged portion 149, which tapers, as shown at 150, to a smaller diameter, as shown at 151. The tapered portion 150 of the screw 148 is adapted to engage in an aperture 152 in one head of the reel 41 and the portion 151 of the screw 148 is shown threaded at 153 to engage a correspondingly threaded portion in the bearing 147. The bearing 147 carries a finger 154 adapted to engage in an aperture 155 in the other head of the reel 41, whereby the reel 41 may be fixed to the bearings 146 and 147.

The right end (Fig. 4) of the bearing 147 has a sprocket 160 rotatable thereon and provided with a clutch face 161, which is normally engaged by a cooperating clutch face 162 formed on a collar 163 formed integral with a hand wheel 164. The collar 163 is normally urged to the left (Fig. 4) by a series of coil springs 165 seated in pockets in the collar and abutting a hand wheel 166. Adjacent their peripheries, the hand wheels 164 and 166 have radially extending plates 167 and 168 welded to them and the hand wheel 166 has an axially extending ring 169 fixed to it for supporting coil springs 170 in the space between adjacent plates 167 and 168, whereby the two hand wheels will be urged to rotate together. The springs 165 normally hold the clutch face 162 in engagement with the clutch face 161 so that the rotation of the sprocket 160, by the chain 130, will drive the hand wheel 164, and the springs 170 interposed between the plates 167 and 168 will tend to drive the hand wheel 166 with the sprocket. The hand wheel 166 is fixed to the bearing 147 and there-

fore the sprocket 160 will resiliently drive the bearing 147 to rotate the reel 41. Suitable markings are placed on the hand wheel 164 and 166 and the tension of the brake shoes 91 and 92 on the brake drum 90 may be regulated to drive the takeup reel 41 under the desired tension, as indicated by the displacement of the hand wheel 164 with respect to the hand wheel 166.

Mounted in the bottom end of the casing 134, as shown in Figs. 4 and 8, is a block 180 having the configuration at its left end (Fig. 8) of half a nut, that is, half a thread is formed in the block 180 to cooperate with a screw 181. The block 180 is provided with a handle 182, whereby it may be withdrawn from engagement with the screw 181 provided a spring-pressed plunger 183 has been withdrawn from a socket 184 in the block 180. The screw 181 is journaled in a side member 185 and a side member 186 of the cradle 75 and carries on its left end (Fig. 4) a gear 187, which meshes with a gear 188 mounted on the shaft 127.

The side members 185 and 186 of the cradle 75 are joined together at their upper ends by an angle member 171 and they are joined together at their bottom ends by another angle member 172. The angle members 171 and 172 have track members 173 and 174, respectively, fixed to them for engagement by rollers 175—175 rotatably mounted on the angle members 171 and 173 of the reel supporting frame. As shown in Figs. 3 and 4, two rollers 175 engage a horizontal surface of the track member 173, two rollers 175 engage a vertical surface of the track member 173, two rollers 175 engage a vertical surface of the track member 174, and two rollers 175 engage a horizontal surface of the track member 174. From the foregoing, it is believed to be apparent that the reel supporting frame may be slid back and forth on the cradle 75 to move the reel 41 mounted thereon back and forth with respect to the guide member 79 to distribute the cable 20 on the reel 41.

As shown in Fig. 6, the shaft 127 is connected through the clutch member 126 to the gear 121, whereby the reel supporting frame will be driven to the left (Fig. 4) and this drive of the reel supporting frame to the left (Fig. 4) will continue until the angle member 136 engages a collar 190 fixed to a shaft 191 and slideable in the transmission housing 123. The collar 190 is pinned to the shaft 191 at 192 and a corresponding collar 193 is pinned to the shaft 191 at 194. The collars 190 and 193 have pockets 195 and 196 formed therein in which coil springs 197 and 198, respectively, are seated. The coil springs 197 and 198 abut a shoulder 199 formed on a sleeve 200, which is slideable on the shaft 191. The shoulder 199 has an extension 201 formed thereon which enters a slot 202 in a ring 203 fixed to the clutch member 126. A pair of latches 204 and 205 (Fig. 7) cooperate with the shoulder 199 to hold it in either of two positions, being urged into engagement with the shoulder by coil springs 206 and 207, respectively.

The just described mechanism comprises what is commonly known as a "load and fire" mechanism, which will hold the clutch member 126 in engagement with either the clutch face 125 or the clutch face 129, into which positions the clutch member will be moved by the snap action of the springs 197 or 198 when the collar 190 or the collar 193 engages the angle members 135 or 136. When the clutch member 126 is moved from engagement with the clutch face 125 into

engagement with the clutch face 129, the direction of rotation of the screw 181 will be reversed and the screw will continue to rotate in said reversed direction until the "load and fire" mechanism is reversed again by the forcing of the shaft 191 in the opposite direction, whereupon the direction of rotation of the screw will again be reversed and it will drive in the direction originally described to thus distribute the cable 20 on the reel 41.

It is believed that the following brief description of the mode of operation of the mechanism will aid materially in an understanding of the mode of operation of the apparatus.

After a group of wires and spacers have been assembled, they will be fed through the rollers 40, which will hold the assembled wires and cables from rotation at the point where the rolls engage the wires and spacers, and as the assembled wires and spacers are drawn onto the takeup reel 41, they will have the layers of tape applied to them and will be twisted. In starting the machine, the cable may be wrapped around the reel 41 by hand and the tension on the cable regulated by adjusting the hand wheel 102, which controls the brake shoes 91 and 92, until the desired amount of displacement occurs between the hand wheels 164 and 166. The motor 50 may then be started to rotate the reel cradle 75 to impart either a right-hand or left-hand spiral twist to the assembled wires as they are drawn upon the reel 41. The direction of twist imparted to the cable may be changed by either using the shaft 84 in the position in which it is shown or by transferring it to the position now occupied by the shaft 87, providing the necessary adjustments are made on the chain tightener, not shown. The reel cradle rotates within the bearing 77 and as the cradle rotates, it carries with it the shaft 106 having the gear 105 in mesh with the ring gear 104. The ring gear 104, being fixed to the brake drum 90, will be permitted to rotate only when there is a predetermined tension on the cable 20 and therefore, if the brake shoes 91 and 92 were released from the brake drum 90, the brake drum and ring gear 104 would be free to rotate and no motion would be imparted to the takeup reel 41. However, when brake pressure is applied to the brake drum 90, there will be a speed variation between the drum 90 and the cradle 75, whereby the gear 105 will proceed to walk about the ring gear 104, rotating the shaft 106 and rotating the takeup reel through the beveled gears 120 and 123, shaft 124 and chain 130 driven from the shaft 124.

The tension under which the cable is drawn through the machine will be indicated by the relative displacement of the hand wheels 164 and 166 in the following manner. The reel 41 is driven by the sprocket 160, the clutch face 121 of which meshes with the clutch face 125 on the collar 163 formed integral with the hand wheel 164, which is in turn connected through the springs 170 to the hand wheel 166 fixed to the bearing 147, on which the reel is secured. As tension increases on the cable being drawn through the machine, the hand wheels 164 and 166 will be displaced relative to each other as the springs 170 are compressed and the amount of displacement will be the measure of the amount of tension on the cable, and when this tension has increased to the desired amount, the brake shoes 91 and 92 may be released to permit the brake drum 90 to rotate with that predeter-

mined amount of displacement between the hand wheels 164 and 166.

It is believed to be thus apparent that the reel 41 may be rotated in timed relation to the drive 5 of the carrier chain while maintaining the cable being reeled on the reel under a selected tension. As the reel rotates to wind the cable 20 on it, the framework, comprised of the angle members 135, 136, 137 and 138, which carry the reel, will 10 be shifted across the cradle 75 by the distributing mechanism, which includes the screw 181 and the block 190, and as the reel moves across the cradle during the rotation of the cradle, the cable 20 will be distributed across the drum of the reel 15 from one head thereof to the other, the direction of rotation of the screw 181 being reversed each time one of the collars 190 or 193 is pushed against its associated angle member 136 or 135, with sufficient force to snap the latches 204 or 20 205 into and out of latching engagement with the shoulder 199.

Although a specific embodiment of the invention has been described herein, it will be understood that the construction shown is subject to 25 numerous modifications and that applicant's invention is to be limited only by the scope of the appended claims.

What is claimed is:

1. In a cable-making apparatus, a takeup reel, 30 a cradle for supporting the reel, means for rotating said cradle to impart a twist to the cable, a drive shaft carried by said cradle for driving the reel, a differential brake mechanism for rotating said shaft, and compressible means between the shaft and the reel for transmitting motion from the shaft to the reel.
2. In a cable-making apparatus, a takeup reel, 35 a cradle for supporting the reel, means for rotating the cradle, means for rotating the reel with respect to the cradle comprising a reel driving member, a driven member associated with said reel driving member, and a compressible means interposed between said members for transmitting motion from the driven member to the driving member to rotate the reel.
3. In a cable-making apparatus, a takeup reel, 40 a cradle for supporting the reel, means for rotating the cradle, means for rotating the reel with respect to the cradle comprising a reel driving member, a driven member, resilient means interposed between said members, and a differential device for driving said driven member.
4. In a cable-making apparatus, a takeup reel, 45 a cradle for supporting the reel, means for rotating the cradle, means for rotating the reel with respect to the cradle comprising a reel driving member, a driven member, resilient means interposed between said members, and a differential device actuated by the cradle for driving said driven member.
5. In a cable-making apparatus, a takeup reel, 50 a rotatable cradle for supporting said reel, means for rotating the reel with respect to the cradle comprising a differential braking device for driving the reel, and compressible means interposed 55 between the reel and the braking device for trans-

mitting motion from the braking device to the reel.

6. In a cable-making apparatus, a rotatable cradle, a reel rotatably mounted in said cradle, a pair of bearings for rotatably supporting the reel in the cradle, means for driving the reel comprising a pair of wheels, means for resiliently interconnecting said wheels, and a differential braking device actuated by the rotation of the cradle for actuating one of said wheels. 10

7. In a cable-making apparatus, a rotatable cradle, a reel rotatably mounted in said cradle, a pair of bearings for rotatably supporting the reel in the cradle, means for driving the reel comprising a pair of wheels, means for resiliently connecting said wheels, a differential braking device actuated by the rotation of the cradle for actuating one of said wheels, and means for adjusting the differential braking device to maintain said wheels in a predetermined relation during 20 their rotation. 15

8. In a cable-making apparatus, a rotatable cradle, a reel rotatable in said cradle, a floating ring gear, means for retarding rotation of said ring gear, a gear movable bodily about the ring gear, and a resilient reel driving member driven by said last mentioned gear when the ring gear is retarded. 25

9. In a cable-making apparatus, a rotatable cradle, a reel rotatable in said cradle, a floating 30 ring gear, means for retarding rotation of said ring gear, a gear movable bodily about the ring gear, a resilient reel driving member driven by said last mentioned gear when the ring gear is retarded, and means for adjusting said retarding 35 means. 40

10. In a cable-making apparatus, a rotatable cradle, a reel rotatable in said cradle, a floating ring gear, means for retarding rotation of said ring gear, a gear movable bodily about the axis 45 of the ring gear, a resilient reel driving member driven by said last mentioned gear when the ring gear is retarded, and means for adjusting said retarding means to effect the resilient means a predetermined amount. 45

11. In a cable-making apparatus, the combination with a rotatable cradle, a reel rotatable in said cradle, and means for rotating said cradle, of a differential braking device, a shaft adapted to be driven by said braking device, and a resilient 50 means interconnecting said shaft and the reel. 50

12. In a cable-making apparatus, the combination with a rotatable cradle, a reel rotatable in said cradle, and means for rotating said cradle, of a differential braking device, a shaft adapted to be driven by said braking device, a resilient means interconnecting said shaft and the reel, said resilient means comprising a rotatable reel supporting member, a hand wheel fixed to said member, a second hand wheel cooperating with the 60 first hand wheel, and a plurality of springs interconnecting the hand wheels. 60

LILA T. JOHNSON,
Executrix of the Estate of Fred V. Johnson, De-
ceased.
